TYPE-WRITING MACHINE.

1,171,326.

Specification of Letters Patent.

Patented Feb. 8, 1916.

Application filed May 10, 1913. Serial No. 766,672.

To all whom it may concern:

Be it known that I, ADOLPHUS S. DENNIS, a citizen of the United States, residing in Lakewood, in the county of Cuyahoga and 5 State of Ohio, have invented certain new and useful Improvements in Type-Writing Machines, of which the following is a specification.

My invention relates to line-space indicating devices for use on typewriting machines, and is especially adapted for what is commonly known as "condensed record" work. In work of this character, bills or invoices are made out on sheets provided 15 with printed forms or headings, which sometimes occupy considerable space. Carbon copies of the typewritten portions of a number of bills are made on a single "condensed record" sheet or ledger sheet which is usually longer than the individual bill sheets, 20 the carbon records being printed in succession on the record sheet, and each occupying generally a comparatively small space.

An object of my invention is to provide 25 improved line-space indicating scales and means in connection therewith to control the positions of the scales relative to the platen and thereby facilitate the removal of a bill and replacing of a new bill sheet on the record sheet by indicating the exact distance 30 the platen is to be rotated. Parallel finger wheels or disks are loosely mounted on the platen axle and independently rotatable thereon. On the periphery of each disk is 35 a series of scale numbers at line-space distances apart, the numbers being in the opposite order on the two disks. An indicator arm on the platen frame extends over the disks and in the path of stops on the disks, 40 each stop being located adjacent to the scale number "1" on its disk. Each stop is held in a projected position, but is adapted to yield in one direction and allow the stop to pass the said arm to permit the use of the indicator when the platen is rotated more than a complete revolution in bringing a bill or invoice sheet to writing position.

Other objects of the invention will appear hereinafter.

In the accompanying drawings, Figure 1 is a plan view of a portion of a typewriting machine with my invention applied thereto. Fig. 2 is an end elevation view of the same, partly in section, the view being taken from the right-hand end of Fig. 1. Fig. 3 is

a sectional view of the indicator attachment and associated parts. Fig. 4 is a perspective view of the same. Fig. 5 is a detail view showing the yielding stops on the indicator disks.

The present invention is a modification of the invention shown in patent to Briggs 916,099, and is herein shown as applied to a Remington No. 6 typewriter, although it is to be understood that the invention is applicable to other typewriting machines. The traveling carriage 1 is supported on rollers 2, which travel on a stationary rod or rail 3 mounted on the top plate of the machine. The platen frame 4 is supported on its rear side by means of links 5 connected with the carriage, and at its front side by means of a roller 6, which travels on a shift rail 7. The platen 8 is rigidly secured to the platen axle 9, journaled in the end bars of the platen frame. The platen frame comprises a bar 10 to which are pivoted hangers 11 which support a shaft 12 carrying the usual feed roller or rollers 13. Springs 15 secured to the hangers 11 by screws 16 engage lugs 17 projecting from the bar 10, said springs normally pressing the feed rollers against the platen. The feed rollers may be disengaged from the platen by means of a finger piece 18 forming the end of a crank arm, 80 which is rigidly mounted on a rock shaft 19 pivoted in the platen frame, said rock shaft is provided with projections 20 which engage the hangers 11. When pressure is applied to the finger piece 18 the projections 85 20 bear against the hangers 11 and lift the feed rollers from the platen. On the right-hand of the platen roller is mounted a line-space ratchet wheel 21, with which co-operates a feed dog or pawl 22 to feed the platen 90 forward in the usual way. The pawl 22 is pivotally mounted on an arm 23, which is connected to the platen frame by a pivot 24, said arm being integral with the usual carriage returning line-space lever 25. Secured on the ends of the platen axle are the 95 usual finger wheels 26 and 27.

The line-space indicating mechanism comprises hand wheels or disks 28 and 29 loosely mounted on a hub 30, the latter being fixed to the platen axle 9. The hub 30 is formed with a central flange 31, which serves to space the disks so that they may rotate entirely independently of each other. The 105 disks are held in frictional contact with 110

said flange by means of leaf springs 32 bifurcated to straddle the hub 30 and held in position by annular grooves 33 in said hub. On the periphery of the disk 28 is a line-space scale comprising numbers "1," "2," "3," etc., at line-space intervals, the numbers corresponding in number and position to the ratchet teeth on the line-space wheel. On the disk 29 is a similar scale but the numbers in this instance are arranged in the reverse order. The scales are preferably printed in different colors or on differently colored backgrounds, or are otherwise provided with distinguishing characteristics.

Secured to the platen frame is an indicating or index arm 35, projecting over the disks and located in the path of the stops 36 and 37. Each of these stops is pivoted in a recess 38 formed in the disk and is held in a projecting position by a spring 39; thus the stop 37, as shown in Figs. 4 and 5, is projected in a position to be intercepted by the arm 35 and thereby prevent the rotation of the disk 29 in a forward direction beyond the position shown in Fig. 4. Stop 37, however, will yield in the opposite direction to pass the arm 35 during the backward rotation of the disk. The stop 36 is likewise yieldable to permit it to pass the stop arm 35 but in the reverse direction. The under surface of the arm 35 may be beveled to assist in camming the stops 36 and 37 downward as the latter pass beneath said arm.

The invention may be used as follows: The scales are rotated on the platen axle to the position shown in Fig. 1 with the stop 36 against the upper edge of the arm 35 and the stop 37 against the lower edge of said arm. A "condensed record" or ledger sheet and an invoice sheet or bill may now be placed on the machine with an interposed carbon sheet, the record sheet being placed next the platen. These sheets are placed with their forward edge against the pressure rolls or other limiting devices. The platen is then rotated in a forward direction until the printed heading on the invoice sheet has passed beyond the printing line and the sheet is in position to receive the typewritten record. During this forward rotation of the platen the disk 28 is carried therewith, the disk 29 being held stationary by the stop 37 in contact with the arm 35. When the work sheets are thus in position for writing, the scale number on the disk 28 appearing directly over the indicator arm 35, is noted. Assuming, for example, that this number is "24" as shown on Fig. 4, it indicates that the platen has been rotated a distance of twenty-four line-spaces in bringing the work sheets into writing position. After the desired record has been made on the invoice and record sheet, which record may comprise one or more lines of typewritten matter, the platen is rotated

backward carrying with it the disk 29 until the scale number "24" thereon appears directly below the indicator 35; that is, the platen is rotated backward through twenty-four line spaces, or in other words the platen is rotated backward through the same distance as it was rotated forward to bring the invoice sheet into position to receive the first line of writing, the opposite reading of the numbers on disk 29 enabling the operator to return the platen through exactly the number of line spaces it had been advanced to start the first line of writing, the additional line spacing to accommodate the added lines of writing having prepared the record sheet to receive items in succeeding lines. The pressure rolls are now lifted and the invoice sheet or bill removed from the machine without further rotating the platen, the operator holding the record sheet stationary, if necessary, during the removal of the invoice sheet. A new invoice sheet or bill is now placed on the machine after the pressure rolls have been returned, and the platen is rotated in a forward direction until the stop 37 is again brought up to the arm 35. The new invoice sheet is now in position to receive its typewritten record. The record sheet is also in advance of the invoice sheet a distance corresponding to the number of lines written on the first invoice sheet, that is, the record sheet is in position to receive a second invoice record directly below the first. The spacing between the records on the record sheet may be effected by operating the line-space lever after each invoice sheet has been completed but before the platen has been rotated backward to permit the sheet to be removed. When the second invoice record has been completed the platen is again rotated backward as before until the number "24" on the disk 29 appears below the arm 35. The second invoice sheet is now removed the same as the first and the cycle of operation is repeated as many times as desired or until the available space on the record sheet is filled. If the printed heading on the invoice sheet is of such depth as to require more than a complete rotation of the platen to bring the sheet into position for writing, the stop 36 will be brought around to the lower side of the arm 35, and pass behind and beyond said arm to a point above the arm during the insertion of the sheet. This will be noted by the operator and when the invoice sheet is in position the number directly above the arm 35 will be noted as before. If we assume for example, that the disk 28 has made more than a complete rotation and the number "4" appears above the indicator arm, then when the invoice sheet is being removed from the machine the platen is rotated backward more than a complete rotation, the swinging stop 37 on the disk 29 passing beneath the indi- 130

5 cator arm 35 and the rotation being continued until the number "4" on the disk 29 appears below said arm. The platen is now in position for the invoice sheet to be removed as before and another sheet placed in position.

10 It will be seen that the disk 28 with its scale serves to measure the number of line spaces from the upper edge of the invoice, bill or work-sheet to the first line of writing, and after this number has been determined for the first of any series of work-sheets with equal top margins or headings, the disk 29 is used to gage the forward and 15 backward rotation of the platen in positioning work-sheets thereon and removing them therefrom.

20 The present invention is also adapted for use as a page indicating device to enable the operator to determine when the work-sheet has been completed or written upon to a point within a predetermined distance from the bottom edge of the work-sheet. For this 25 purpose either of the indicator wheels or disks may be employed. If the disk 28 is used for this purpose, it may be set as in Fig. 1, prior to the insertion of a work-sheet, so that as the work-sheet is fed forward during the writing of the page, the 30 line-space numbers on said disk appear in succession above the indicating arm 35, and thus indicate the distance of the printing line from the top of the work-sheet. The distance from the top edge of the sheet to 35 the last line it is desired to write on the page, being known or determined by experiment, the numbers on the disk as they pass the indicating arm 35, indicate to the operator the nearness of the sheet to position to receive 40 the final line of writing. For example, with a work-sheet on which the bottom line of writing is twenty-four line-space distances from the top edge, the disk 28 when it reaches the Fig. 4 position with the line 45 space number "24" above the indicating arm, shows that the position for the last line of writing has been reached. It will be noted that the disk is equally well adapted for use as a page-end indicator with a work- 50 sheet of such length that more than a complete rotation of the platen takes place during the writing of the page, as the stop 36 can pass freely beneath the arm 35, and may do so one or more times during the 55 writing of a page, depending on the length of the page. The disk 29 may also be used as a page-end indicating device, the disk in this instance being so set that it will be brought to the Fig. 4 position when 60 the work-sheet is in position to receive the last line of writing. In other words, the disk 29 is set prior to the insertion of the work-sheet so that the number below the indicating arm 35 represents the number of 65 line-space distances from the top edge of

the work-sheet to the last line of writing on the sheet, and, therefore, the numbers on the indicator which pass the indicating arm in the descending order, indicate directly the number of lines to be written to complete 70 the work-sheet. The operator may thus tell at a glance the nearness of the work-sheet to the last line position, by noting the indicator number at the gage 35.

Variations may be resorted to within the 75 scope of the invention, and portions of the improvements may be used without others.

Having thus described my invention, I claim:

1. In a typewriting machine, the combination with a rotary platen, of a line-space indicator rotatable therewith, a stop operative to positively limit the rotation of the indicator in a forward or line-spacing direction and permitting an unlimited rotation of the 85 indicator with the platen in the opposite direction, and a series of indicating numbers brought into indicating position in ascending order as the platen is rotated backwardly from the stop position, thereby indicating 90 directly the number of line-space distances through which the platen has been rotated backwardly from the stop position.

2. In a typewriting machine, the combination of a rotary platen, an indicator having 95 a frictional driving connection therewith to permit the indicator to rotate with the platen in either direction, a stop permanently in operative position to limit the rotation of the indicator in a forward or line-spacing 100 direction and permitting the indicator to rotate with the platen through more than one complete rotation of the platen in the opposite direction, and a series of indicating numbers brought into indicating position in 105 ascending order as the platen is rotated in said opposite direction from the stop position.

3. In a typewriting machine, the combination with a rotary platen, of a line-space 110 indicator having a frictional driving connection therewith, a stop continuously in operative position to limit the rotation of the indicator in line-spacing direction whenever the indicator reaches a position determined by said stop, said stop permitting an unlimited rotation of the indicator in the reverse direction, and a series of indicating numbers arranged to indicate directly 115 as the platen is rotated in said reverse direction, the number of line-space distances through which the platen has been rotated from the stop position.

4. In a typewriting machine, the combination with a rotary platen, of a disk mounted 125 on the platen axle and having a frictional driving connection therewith to cause the disk to rotate with the platen in either direction, a stop on said disk, a stationary stop in the path of said first-mentioned stop 130

- and limiting the rotation of the disk with the platen in line-spacing direction, and a line-space indicating scale on the disk provided with indicating numbers arranged to be brought into indicating position in ascending order as the platen is rotated backwardly from the stop position.
5. In a typewriting machine, the combination of a rotary platen, disks mounted on the platen axle and rotatable independently of each other and of the platen, said disks being frictionally held for rotation with the platen, line-space indicating characters on the disks, stops on the disks, and a coöperating stationary stop to limit the rotation of each disk.
10. In a typewriting machine, the combination with a rotatable platen, of an index disk rotatable therewith, and an index arm forming a stop for the disk to positively limit the rotation of the disk with the platen as the latter is rotated in line-spacing direction, said disk capable of an unlimited rotation with the platen in the reverse direction, and a scale comprising a series of index numbers arranged to be brought into indicating position in ascending order as the platen is rotated in said reverse direction, and indicating directly the distance through which the platen has been rotated in said reverse direction from the stop position.
15. In a typewriting machine, the combination with a rotary platen, of index disks frictionally mounted on the platen axle, stops on said disks, and a stationary index arm in the path of said stops and limiting the rotation of each disk in one direction.
20. In a typewriting machine, the combination with a rotary platen, of index wheels frictionally mounted on the platen axle, stops on said wheels, and a stationary index arm in the path of said stops, said stops each being yieldable in one direction to permit an unlimited rotation of its index disk in the said direction.
25. In a typewriting machine, the combination of a rotary platen, index disks mounted on the platen axle and frictionally held against rotation independently of the platen, a stationary index arm, a stop on one of said disks to engage said arm and limit the rotation of said disk in one direction and yieldable in a reverse direction to pass said index arm, and a stop on the other disk adapted to be intercepted by said arm and yieldable in the reverse direction from said first named stop.
30. In a typewriting machine, the combination with a rotatable platen, of index disks mounted on the platen axle and frictionally held against rotation independently of the axle, an index on each disk comprising a series of numbers, the numbers on the two disks being arranged in the reverse order, a stop on each disk located at the beginning of the series of numbers, and a co-operating stationary stop.
35. In a typewriting machine, the combination with a rotatable platen, a hub secured to the platen axle and comprising a central flange, index disks mounted on said hub on opposite sides of the flange, bifurcated springs held in annular grooves in said hub and bearing against said disks, a line-space index on each of said disks, and stops to limit the rotation of said disks on the platen axle.
40. In a typewriting machine, the combination of a rotatable platen, index disks frictionally mounted on the platen axle, and means to prevent rotation of one of the disks with the platen in one direction from an initial position and to prevent rotation of the other disk with the platen in the reverse direction from an initial position.
45. In a typewriting machine, the combination with a rotary platen, of a line-space indicator rotatable therewith, a stop to limit the forward rotation of the indicator when the indicator has reached a predetermined position and permitting an unlimited rotation of the indicator with the platen in the reverse direction, a series of indicating numbers on said indicator, and a stationary index or pointer in position to indicate the first number of said series when the indicator is at the forward limit of its rotation determined by said stop, said numbers arranged to pass said indicator in the ascending order as the platen is rotated backwardly from said position.
50. In a typewriting machine, the combination with a rotary platen, of an indicator having a friction driving connection with the platen, causing the indicator to rotate with the platen and permitting the platen to rotate independently of the indicator when the latter is restrained, a stop to limit the backward rotation of the indicator with the platen but permitting an unlimited rotation of the indicator with the platen in a forward direction, a series of numbers on said indicator to indicate rotations of the platen through line-space distances, and an index or pointer past which said numbers are carried during the rotation of the indicator with the platen, said pointer positioned at the first number of said series when the indicator is at the limit of its backward rotation determined by said stop, said numbers passing the pointer in the ascending order as the platen is rotated forwardly.
55. In a typewriting machine adapted for use as a billing machine, the combination with a rotary platen, of indicating mechanism to indicate the extent of the forward and backward rotation of the platen for inserting and removing bills or work-sheets, said mechanism comprising an indicator

frictionally connected to rotate with the platen and permitting independent rotation of the platen when the indicator is restrained, a stop on said indicator to limit the backward rotation of said indicator, and permitting unlimited forward rotation thereof, a series of numbers on said indicator, and a stationary arm forming a counter-stop for said stop, and also forming a pointer past which said numbers are carried as the indicator rotates, said pointer being at the beginning of said series when the indicator is at the limit of its backward rotation determined by said stop, said numbers being carried past the pointer in the ascending order as the platen is rotated forwardly to bring a bill or work-sheet into position to receive the first line of writing, said bill having been placed on the machine when the indicator is at said stop position, whereby the said numbers indicate directly the distance through which the platen is rotated, a second indicator frictionally connected to rotate with the platen and permitting independent rotation of the platen when said second indicator is restrained, a stop to limit the forward rotation of said second indicator but permitting unlimited backward rotation thereof, and a series of numbers on said second indicator arranged to move past said pointer in the ascending order as the platen is rotated backwardly, said pointer being at the beginning of said last-named series of numbers when said second indicator is at the limit of its forward rotation, whereby the distance through which the platen is rotated backwardly to bring the bill or work-sheet into position to be removed from the machine, is indicated directly by the numbers on said second indicator.

16. In a typewriting machine adapted for use as a billing machine, the combination with a rotary platen, of indicating mechanism to indicate the extent of the forward and backward rotation of the platen during the placing and removal of bills or work-sheets on and from the platen, said mechanism comprising an indicator frictionally connected to rotate with the platen and permitting independent rotation of the platen when the indicator is restrained, a stop to limit the backward rotation of said indicator and permitting unlimited forward rotation thereof, a series of numbers on said indicator, a stationary pointer past which said numbers are carried as the indicator rotates, said pointer being at the beginning

of said series when the indicator is at the limit of its backward rotation determined by said stop, said numbers being carried past the pointer in the ascending order as the platen is rotated forwardly to bring a bill or work-sheet into position to receive the first line of writing, said bill having been placed on the machine when the indicator is at said stop position, whereby the said numbers indicate directly the distance through which the platen is rotated, a second indicator frictionally connected to rotate with the platen and permitting independent rotation of the platen when said second indicator is restrained, a stop to limit the forward rotation of said second indicator but permitting unlimited backward rotation thereof, and a series of numbers on said second indicator arranged to move past said pointer in the ascending order as the platen is rotated backwardly, said pointer being at the beginning of said last-named series of numbers when said second indicator is at the limit of its forward rotation, whereby the distance through which the platen is rotated backwardly to bring the bill or work-sheet into position to be removed from the machine, is indicated directly by the numbers on said second indicator.

ADOLPHUS S. DENNIS.
